UNITED STATES PATENT OFFICE

MARGARET C. REVIS, OF WEAVERVILLE, NORTH CAROLINA, ASSIGNOR TO ALLAN-STAND COTTAGE INDUSTRIES, INCORPORATED, OF ASHEVILLE, NORTH CAROLINA, A CORPORATION OF NORTH CAROLINA

DESIGN FOR A CORN-SHUCK DOLL

Application filed April 10, 1930. Serial No. 35,208. Term of patent 7 years.

To all whom it may concern:

Be it known that I, MARGARET C. REVIS, a citizen of the United States of America and residing in the city of Weaverville, in the county of Buncombe and State of North Carolina, have invented a new, original, and ornamental Design for Corn-Shuck Doll, of which the following is a specification, reference being had to the accompanying drawing, forming part thereof.

In the accompanying drawings, Fig. 1 is a front elevation of a doll showing my new design and Fig. 2 is a side elevation of the same.

I claim:

The ornamental design for a corn-shuck doll, as shown.

MARGARET C. REVIS.
